CLAIM

The ornamental design for a headlamp, as shown and described.

DESCRIPTION

FIG. 1 is a front and top perspective view of a headlamp design showing my new design.

FIG. 2 is a rear and bottom perspective view of a headlamp.

FIG. 3 is a front view of a headlamp.

FIG. 4 is a rear view of a headlamp.

FIG. 5 is a left side view of a headlamp.

FIG. 6 is a right side view of a headlamp.

FIG. 7 is a top view of a headlamp.

FIG. 8 is a bottom view of a headlamp.

FIG. 9 is an enlarged view of a headlamp in area "9" of FIG. 1; and,

FIG. 10 is an enlarged view of a headlamp in area "10" of FIG. 2.

Any shading and cross-hatching are not features of the design but are utilized to illustrate the surface contours of the headlamp design in the drawings.

The broken lines around the enlargement indicia in FIGS. 1-2 and 9-10 are shown for the purpose of illustrating the bounds of the enlargements and form no part of the claimed design.
